T. SHIPLEY.

MACHINERY FOR THE MANUFACTURE OF ICE.

APPLICATION FILED APR. 19, 1915.

1,158,320.

Patented Oct. 26, 1915.

Attorney

UNITED STATES PATENT OFFICE.

THOMAS SHIPLEY, OF YORK, PENNSYLVANIA.

MACHINERY FOR THE MANUFACTURE OF ICE.

Specification of Letters Patent.

Patented Oct. 26, 1915.

1,158,320.

Application filed April 19, 1915. Serial No. 22,354.

To all whom it may concern:

Be it known that I, THOMAS SHIPLEY, of the city of York, in the county of York and State of Pennsylvania, have invented a new and useful Improvement in Machinery for the Manufacture of Ice, of which the following is a specification.

My invention relates to the can system for making ice, and more particularly to that system in which air under pressure is injected into the body of water in the can at or near the bottom to prevent impurities in the water from being incorporated in the ice during the freezing operation.

It has to do more particularly with the construction and arrangement and fitting together of the can and the tube through which air is injected into the interior of the can, the object being primarily to reduce the cost of manufacture, and furthermore to obtain an effective and easily manipulated union of the can and tube, and one which will permit the ready repair or replacement of the tube whenever desired.

I shall first describe my improvement in connection with the accompanying drawings, and will then point out more specifically in the claims those features of the same which I believe to be new and of my own invention.

In the drawings—Figure 1 is a view of the can with the air tube applied; Fig. 2 is an enlarged vertical section through the air tube side of the can on line 2—2, Fig. 1; Fig. 3 is an enlarged cross section on line 3—3, Fig. 2.

The can is shown at A. It is made of sheet metal as usual, and can be of any convenient or preferred construction and shape—of rectangular cross section in the present instance.

B is the wrought iron reinforcing band at the top of the can.

In one of the longer sides of the can is formed the external vertical groove C of approximately U or V cross section, which extends from the top of the can to near the bottom of the same. A hole f in the lower end of the groove opens into the interior of the can. This construction permits of the use of a straight length of air tube, only the lower portion of which extends into the can.

D is the air tube. It is inserted in the groove C from the top of the can, between the band B and the grooved side of the can, and is thence pushed along down in the

groove C through the hole f in the lower end of the same into the inside of the can until its beveled lower end d is near enough to the bottom of the can to secure proper circulation of the air discharged from it. In the drawing the beveled end is shown as reaching to the can bottom, but this is not necessary. The portion of the air tube D which is held in place by the band B is cylindrical, and is reamed out on a taper to receive the air nozzle (indicated in dotted lines, Fig. 2). Below this point the tube is preferably somewhat flattened on its exposed side, as seen at c, so that it shall not materially project beyond the side of the can. The depth of the groove C relatively to the dimensions of the tube preferably should be such that when the tube is seated therein the external flat side c of the tube shall be practically flush with the outside of the can, the tube in this way being shielded and protected from accidental injury in handling the can.

The beveled end d of the tube D is the only air nozzle needed. Air discharged from that end will be forced toward the vertical center line of the can.

The hole f in the lower end of the groove C is of shape and size to closely fit the tube D which passes through it; and the tube and side of the can are soldered together at this point to make a tight joint. This is the only point where soldering between the can and air tube is required, the tube, held in place above by suitable means—in this instance by the wrought iron band B—being free to expand and contract without liability of being loosened, distorted or thrown out of place. The tube and can may also be united, by solder if desired, at other points between the lower end of the groove C and the top of the can, but this is not indispensable.

The groove C in the present instance is located on the center line of the can side. It is on this line that the blocks of ice are sawed or split in dividing them up for the retail trade; and the internally projecting rib furnished by the groove C makes a mark or indentation in the ice block which facilitates its after division along that line.

The shape of the tube D not only protects it from injuries due to rough handling of the can, but it also prevents it from bursting if water should freeze in it—its cross sectional shape permitting of its expansion under these conditions. This particular

- shape, however, while desirable, is not indispensable. The tube may be cylindrical throughout, or of any other preferred cross section. It is desirable also that the groove 5 in the exterior of the can should be of such depth relatively to the dimensions of the tube as to bring the latter within the plane of the face of the can in which it is seated. But this also is not indispensable; the depth 10 of the groove may be such that the tube, while seated in it, may project to some extent from it. What is essential is the external groove C in the side of the can, extending from the top of the can part way only to the, 15 bottom, in combination with the air tube seated in the groove and extending through the lower end of the same down into the interior of the can, and suitable means for securing the exposed portion of the tube to 20 the can—the only solder or other tight joint required between the tube and the can being at the point f where the tube passes through the lower end of the groove C from the outside down into the inside of the can.
25. Having described my improvement, what I claim as new and desire to secure by Letters Patent is—
1. A freezing can having in one of its 30 sides an external groove extending from its top part-way to its bottom, in combination with an air tube seated in said external groove with its lower portion extending on the prolongation of the upper portion straight down through the end wall of said 35 groove into the interior of the can and making a water tight joint with the can at that point, and means for holding the air tube in
- said groove against displacement, substantially as and for the purposes hereinbefore set forth. 40
2. A freezing can having in one of its sides an external groove extending from its top to near its bottom, in combination with an air tube seated in said groove so that its exposed side shall be substantially flush with 45 the adjoining external portions of the can, the lower end of said tube projecting on the prolongation of the external portion of the tube straight down through the said wall of said groove into the interior of the can and 50 making a water tight joint with the can at that point, and a strip or band at the top of the can to confine the upper end of the air tube in the groove, substantially as and for the purposes hereinbefore set forth. 55
3. A freezing can having in one of its sides an external groove extending from its top to near its bottom, in combination with an air tube seated in said groove, said tube having a cylindrical upper end and, below 60 that point, being flattened on its exposed side to be substantially flush with the exterior of the can, the lower end of the tube projecting on the prolongation of the external portion of the tube straight down 65 through the end wall of said groove into the interior of the can and making a tight joint with the can at that point, and means to confine the tube in place in the groove, substantially as and for the purposes hereinbefore 70 set forth.

In testimony whereof I affix my signature.

THOMAS SHIPLEY.
